2 SHEETS—SHEET 2.

UNITED STATES PATENT OFFICE.

EMIL STRANSKY, OF DOVER, OHIO, ASSIGNOR TO THE DOVER MANUFACTURING COMPANY, OF DOVER, OHIO, A CORPORATION OF OHIO.

ELECTRICAL SOLDERING-IRON.

1,315,172.

Specification of Letters Patent. Patented Sept. 2, 1919.

Application filed May 27, 1918. Serial No. 236,878.

To all whom it may concern:

Be it known that I, EMIL STRANSKY, a citizen of the United States, resident of Dover, county of Tuscarawas, and State of Ohio, have invented new and useful Improvements in Electrical Soldering-Irons, of which the following is a specification, the principle of the invention being herein explained and the best mode in which I have contemplated applying that principle, so as to distinguish it from other inventions.

My invention relates to electrically heated soldering irons, its objects being to provide an iron of this character which will be mechanically efficient in its construction and in its operation and which at the same time will be assembled in a manner such that it will permit of a ready removal and replacement of its constituent parts. The said invention consists of means hereinafter described and particularly set forth in the claims.

The annexed drawings and the following description set forth in detail certain means embodying my invention, the disclosed means, however, constituting but one of various mechanical forms in which the principles of the invention may be employed.

30 In said annexed drawings:

Figure 1 represents a side elevation of an electric soldering iron embodying my invention.

Fig. 2 represents an axial section of such iron.

Fig. 3 represents a transverse section upon the plane indicated by line III—III in Fig. 2.

Fig. 4 represents a transverse section taken upon the plane indicated by line IV—IV, Fig. 2.

Fig. 5 represents a side elevation of the heating member together with attached parts, the cement filling the upper horizontal grooves in which the resistance wire lies, being omitted.

Fig. 6 represents an axial section of said heating member, taken upon the plane at right angles to the plane of elevation of Fig. 5.

Fig. 7 represents a cross-section taken upon the plane indicated by line VII—VII in Fig. 6.

Fig. 8 represents an axial section of the grip portion of the handle.

Fig. 9 represents a side elevation of the interior portion of the soldering member, Fig. 10 represents a top plan of such portion of the soldering member, and Fig. 11 represents an axial section of the same. 60

Fig. 12 represents a side elevation of the outer detachable portion of the soldering member.

Fig. 13 represents a side elevation of the outer tubular casing member, and Fig. 14 65 represents a bottom plan of same.

Fig. 15 represents a side elevation of one portion of the handle and Fig. 16 an axial section of same.

Fig. 17 represents an end elevation of 70 such handle portion.

The illustrated embodiment of my invention comprises an outer tubular casing member 1 made preferably of a comparatively light steel tubing. Fitting in and readily removable from the interior of this casing member is a tubular member 2 made of non-heat-conducting material such as asbestos or similar material. This non-heat-conducting member, therefore, forms 80 a removable interior lining for the tubular casing member 1. As illustrated, this lining member is of less length than the tubular casing member. Fitting in and removable from the interior of the member 2 is 85 a heating member 3, Figs. 5 and 6. This heating member consists of a tubular element 4 open at one end and closed at the other end by means of a cap 5, both member 4 and cap 5 being made of refractory 90 material such as clay, the cap 5 being suitably cemented in place so as to be permanently secured therein. Mounted upon the exterior of this tubular element 4 is a resistance wire 6 preferably laid in a helical 95 groove 7 and secured in such groove by means of a suitable dielectric cement. An exterior longitudinal groove 8 is formed in the member 4 in which the return portion of the resistance wire may be laid and wherein such returned portion is suitably secured by cementing, the said groove being sufficiently deep to permit this returned portion to be suitably separated from the helical convolutions of the wire, as will be readily understood by those skilled in the art and as clearly shown in Fig. 7. The outer portion of the cap 5 is formed with two aligned 100 grooves 9 in which portions of the resistance wire are laid and cemented, as shown 110

in Fig. 6, the continuation of said wire passing on through ducts 10^a formed in a refractory tube 10 projecting into and detachable from the cap 5. The one groove 9 registers with the longitudinal groove 8. In this manner it will be seen that the resistance wire is completely incased and protected against contact with any of the conducting portions of the device.

10 The soldering element of the iron consists of an inner part 11, Fig. 9, and an outer part 12, Fig. 12. This inner part is formed with a flange 13 and with a body portion 14, the latter projecting into the interior 15 of the heating member 3 and readily removable therefrom, the flange 13 fitting into the interior and forming a closure for the end of the casing member 1 as shown in Fig. 2. The body portion 14 is formed with a groove 15 which receives the longitudinal projection 16 which is formed as a result of the formation of the groove 8 on the exterior of member 4. The outer part 12 of the soldering member is formed with a 20 threaded portion 17 which fits a threaded bore 18 of the interior member 11. This soldering member is secured to the casing member by means of nuts 18^a, Fig. 1, adapted to engage studs 19 secured to the 25 flange 13, which studs pass through slots 19^a in member 1, Fig. 13.

The other end of the casing member is closed by a handle member 20, Figs. 15 and 16, which consists of a tubular portion 21 and a flange portion 22, the latter fitting in the upper end of the casing member and being provided with studs 22^a adapted to be engaged by nuts 23 passing through slots 23^a whereby said handle member is 30 removably secured in place. It will thus be noted that the heating member and interior lining are included between the flange 22 of member 20 and the flange 13 of the soldering member. It will also be noted that all 35 the parts thus far described are readily detachable and hence removable from each other.

The interior of member 20 receives the tube 10 and its exterior is provided with a 40 threaded portion 21^a which engages the threaded interior of a metal ferrule 24 secured to the grip member 25 of the handle. Suitable means are provided for connecting the terminals of the resistance wires 45 with wires 26 of a suitable cord, for connecting the iron with the current supply. These connecting means are, preferably, mounted upon the upper end of the tubular member 20, and incased within the grip 50 member 25.

What I claim is:

1. In an electric soldering iron, the combination of an outer tubular casing member; an inner non-heat-conducting member of tubular form fitting the interior of said cas-

ing member; a heating member consisting of a tubular supporting element of refractory material open at one end and having a resistance element mounted thereon; a soldering member fitting into one end of said casing member and extending into the interior of said heating member; a member fitting into and closing the other end of said casing member; and a suitable handle and electrical connections for said resistance element.

2. In an electric soldering iron, the combination of an outer tubular casing element, an inner non-heat-conducting member of tubular form fitting the interior of said casing member; a heating member consisting of a tubular supporting element and a resistance element mounted thereon; said heating element fitting in and removable from said non-heat-conducting member; a soldering member fitting into one end of said member and extending into the interior of said heating member; removable means for closing the other end of said casing member; a suitable handle; and suitable electrical connections for said resistance element.

3. In an electric soldering iron, the combination of an outer tubular casing member; an inner non-heat-conducting member of tubular form fitting in and removable from the interior of said casing member; a tubular element of refractory material adapted to support a resistance element and fitting in and removable from said non-heat-conducting member; a soldering member adapted to close one end of said casing member and extending into the interior of said heating member; and removable means for closing the other end of said tubular casing member.

4. In an electric soldering iron, the combination of an outer tubular casing member; an inner non-heat-conducting member of tubular form fitting into the interior of said casing member and removable therefrom; a tubular element of refractory material adapted to support a resistance element and fitting in and removable from the interior of said non-heat-conducting member; a soldering member consisting of an interior portion extending into the interior of said heating member and formed with an end flange adapted to fit in and close one end of said casing member; and an outer soldering head removable from said interior portion of said soldering member; and means closing and removable from the opposite end.

5. In an electric soldering iron, the combination of an outer tubular casing member; an inner non-heat-conducting member of tubular form fitting in and removable from the interior of said casing member and forming an interior lining therefor; a tubular element of refractory material open

at one end and closed at the other, and adapted to support a resistance element, said supporting element fitting in and removable from the interior of said non-heat-
conducting member; a soldering member 5 consisting of an inner and an outer member detachable from each other, said inner member projecting into the interior through the open end thereof and formed with a flange
10 adapted to fit in and form a removable closure for the corresponding end of said casing member, and a removable closure for the opposite end of the latter; said non-heat-conducting and tubular supporting element being included between said closing means
15 and flange.

6. In an electric soldering iron, the com-

binatiion of an outer tubular casing member; an inner non heat-conducting member of tubular form fitting in and removable 20 from the interior of said casing member; a tubular element of refractory material supporting a resistance element and fitting in and removable from said non heat-conducting member; a soldering member closing 25 one end of said casing member and extending into the interior of said heating member; a removable element of refractory material for closing the other end of said tubular element of refractory material; and 30 removable means for closing the other end of said tubular casing member.

Signed by me this 17 day of May, 1918.
EMIL STRANSKY.
